UNITED STATES PATENT OFFICE.

JOHN ODEN MORRIS, OF RICHMOND, VIRGINIA.

STEAM-BOILER FURNACE.

SPECIFICATION forming part of Letters Patent No. 634,829, dated October 10, 1899.

Application filed July 22, 1899. Serial No. 724,793. (No model.)

To all whom it may concern:

Be it known that I, JOHN ODEN MORRIS, a citizen of the United States, residing at Richmond, in the county of Henrico and State of Virginia, have invented new and useful Improvements in Steam-Boiler Furnaces, of which the following is a specification.

My invention relates to steam-boiler furnaces; and its object is to provide an improved construction of the same by which atmospheric air can be admitted to the fire-box above the fuel-bed for insuring complete burning of the products of combustion and by which also a forced draft of said air may be employed when desired.

It is also an object to improve the construction generally whereby I secure important advantages with respect to efficiency in use.

The invention consists in the novel construction and combination of parts hereinafter fully described and claimed.

In the accompanying drawings, Figure 1 is a central longitudinal section of a steam-boiler furnace constructed in accordance with my invention. Fig. 2 is a front elevation of the furnace-door, showing the hinged dampers open. Fig. 3 is a similar view, the front of the housing being removed.

In the said drawings, the reference-numeral 1 designates the walls of the furnace; 2, the bridge-wall; 3, the grate; 4, the fuel-opening, and 5 a steam-boiler. The said bridge-wall is formed with openings 6 for the passage of the products of combustion, and located in the combustion-chamber 7 in rear of the bridge-wall, in which the unconsumed products of combustion from the fire-box are ignited and burned, are upper and lower arches 8, which retard the passage of said products, so that they shall be completely consumed.

The numeral 9 designates the ash-pit, and 10 the door thereof.

The numeral 11 designates the furnace-door, which is hollow and comprises the inner perforated side 12, which is adapted to cover and close the fuel-opening, the top and bottom walls, and the front formed with an opening 13. This door is hinged to the front of the furnace and is provided with means for fastening it when closed, as usual. Secured to the front of the said door is a housing 14, rectangular in form and provided with draft-

openings in all four sides. These openings are closed by flat dampers 15, hinged at one end to the housing. Pivoted to each of these dampers is a rod 16. The inner ends of these rods are pivotally connected with the inner end of a horizontally-movable pin 17, which passes through a central boss 18 formed integral with the front 19 of the housing. This pin is formed with a series of notches 20, which are adapted to engage with a lug 21 to hold the pin and dampers in any position to which they may be adjusted. By moving this pin inwardly the hinged dampers, through the medium of the connecting-rods, are opened more or less, as the case may be, and by pulling said pin outward the said dampers are closed.

The numeral 24 designates a horizontal shaft extending across the opening in the front of the furnace-door and is provided with a fan or wind-wheel 25. Formed in the front of the said housing is an air-opening 26, which is opened and closed by a rectangular damper 27, pivotally connected with said front and provided with a handle 28, by which it may be operated.

The operation is as follows: A fire is built upon the grate, as usual, and by opening the hinged dampers of the housing atmospheric air will enter the latter and will escape through the perforations in the inner wall of the furnace-door to the fire-box and will mix with the products of combustion, which latter will be entirely consumed in the combustion-chamber. When an increased or forced draft of air is desired to the fire-box above the fuel, the damper in the front of the housing is opened, when the air rushing in through the same will strike the fan or wind-wheel and will rotate the same and force the air into the combustion-chamber. By reason of the arches in the combustion-chamber the products of combustion from the fire-box will be retarded, so that entire combustion thereof will be insured.

From the above it will be seen that the air is admitted to the fire-box above the fuel-bed, so that it will combine with the unconsumed products of combustion, which will be entirely consumed in the combustion-chamber, thus making a complete smoke-burner. By means of the hinged dampers the amount of

air admitted to the fire-box above the fuel-bed can be regulated as circumstances may require, and through the medium of the wind-wheel and pivoted damper a forced draft can be given to the air when an intense heat is desired.

Having thus fully described my invention, what I claim is—

1. The combination with a steam-boiler furnace, of the hollow hinged door, the perforated inner wall, the front formed with an opening, the rotatable wind-wheel, the housing secured to said front provided with a damper and an air-opening, substantially as described.
2. The combination with a steam-boiler, of the hinged door, the inner wall of which is perforated, and the front formed with an opening, the housing secured to said front provided with hinged dampers at the top, bottom and sides and means for operating the same, substantially as described.
3. The combination with a steam-boiler furnace, of the hinged door having a perforated inner wall and the front formed with an opening, the housing secured to said door, the dampers hinged to the top, bottom and sides thereof, the rods pivotally connected with said dampers, and the horizontally-movable pin to which said rods are pivotally connected, substantially as described.
4. The combination with a steam-boiler

furnace, of the hinged door having a perforated inner wall, and the front having an opening therein, the rotatable wind-wheel, the housing, the pivoted damper in the front thereof, the hinged dampers at the top, bottom and sides, the rods pivotally connected therewith, and the horizontally-movable pin with which said rods are pivotally connected, substantially as described.

5. In a steam-boiler furnace, the door having an inner perforated wall and a radial-bladed valve, or wind-wheel, arranged in an opening in the front wall of said door, and means adapted to direct the air upon the blades of said valve to conduct a blast into the combustion-chamber, substantially as specified.

6. In a steam-boiler furnace, the hollow door, with its interior in communication with the combustion-chamber and having a blasted valve or wind-wheel arranged in an opening in its front, and a valved chamber arranged upon said front and in communication with the interior of said door, substantially as set forth.

In testimony whereof I have hereunto set my hand in presence of two subscribing witnesses.

JOHN ODEN MORRIS.
